REFRIGERATING APPARATUS

Daniel D. Wile, Detroit, Mich., assignor to Detroit Lubricator Company, Detroit, Mich., a corporation of Michigan

Application July 9, 1935, Serial No. 30,440

10 Claims. (Cl. 62—115)

My invention relates generally to refrigerating apparatus and more particularly to refrigerant evaporators therefor.

In the past, refrigerating systems and particularly refrigerating systems having a so-called flooded type of refrigerant evaporator, have not been entirely satisfactory in operation because of a tendency of the lubricant of the system to concentrate in the bottom of the evaporator. The lubricant thus concentrated in the bottom of the evaporator, occupied space which the refrigerant medium should normally occupy and prevented normal transfer of heat to the refrigerant medium with the result that ebullition of the refrigerant was insufficient to obtain satisfactory refrigerating results. In certain types of refrigerant evaporators, the concentration of the lubricant therein is more marked than in other types and to the extent that the efficiency of the system is appreciably affected. In some systems, because of the high concentration of lubricant in the evaporator, it frequently occurs that the refrigerant compressor has to operate an abnormally long period of time before the temperature of the evaporator is decreased to the desired temperature, which is, of course, inefficient operation and objectionable. In addition, when the lubricant concentrates in the evaporator, the compressor is deprived of the benefit of the lubricant and which is also an objectionable condition.

Accordingly, it is an object of my invention to obviate the above-mentioned objectionable conditions in a refrigerating system.

Another object of my invention is to provide a refrigerating system having a flooded type of evaporator and one which has a substantially uniform cycle of operation.

Another object of my invention is to provide for agitating the refrigerant and oil adjacent the bottom of the evaporator so as to obtain proper ebullition of the refrigerant, and so that the oil will circulate through the system and to accomplish this in an economical manner.

Other objects of my invention will become apparent from a reading of the following detailed description in connection with the accompanying drawing which forms a part of my specification, and in which drawing—

Figure 1 is a diagrammatic view of a refrigerating system embodying my invention, and

Fig. 2 is a view shown in vertical cross-section of the refrigerant evaporator shown in Fig. 1.

Referring to the drawing by characters of reference, the refrigerating system includes the usual condensing element which may be of any

suitable type and which comprises a refrigerant compressor 1 and a refrigerant condenser 2, the compressor being driven by an electric motor 3. One end of the condenser coil, as at 4, is connected to the compressor 1 while the other end is connected to a refrigerant receiver 5. The numeral 6 designates, in general, the cooling element or refrigerant evaporator and which, in the present instance, is a flooded type of evaporator. The evaporator 6 includes a header 7 mounted on the top thereof, and connected to the header 7 there is a control device 8 for controlling the admittance of the refrigerant medium to the header to maintain the level of the liquid refrigerant therein at a predetermined level. The control device 8 may be a thermostatic expansion valve or any other suitable control device. A refrigerant supply line or conduit 10 leads from the receiver 5 to the control device 8 and through which liquid refrigerant is supplied to the evaporator by the compressor 1. A return, or suction line, or conduit 11 connects the header 7 and the compressor 1 and through which gaseous refrigerant is withdrawn from the header by the compressor. The thermostatic control device 8 includes a temperature responsive bulb 9 connected thereto by a tube or conduit 9* and which contains a suitable fluid such as methyl chloride, expansible and/or contractible in response to changes in temperature. Preferably the bulb 9 is clamped to the return conduit 11 and adjacent the outlet end of the evaporator.

A thermostatic switch means is preferably provided for cutting-in and cutting-out the compressor between predetermined temperature limits, and comprises a temperature responsive bulb 12, connected by a conduit 13, to a switch means 14. The bulb 12 is preferably clamped to the side wall of the evaporator in good heat transfer relation therewith and contains an expansible-contractible fluid, such as methyl chloride. The switch means 14 is connected by lead wires 15 and 16 to the electric motor 3, and in series circuit with the motor 3 and switch 14 there is a manual switch 17.

The evaporator shown in this instance is constructed of sheet metal forming a top wall 18, a bottom wall 19 and side walls 20, which cooperate to provide an enclosed, open end freezing chamber 21 in which may be placed the usual trays (not shown) for containing water to be frozen. The evaporator 6 may be formed with two sheets of metal, 22 and 23, the inner sheet of which may be flat while the outer sheet of metal may be formed with a plurality of pressed-out ribs 24 forming, with the adjacent

inner sheet, a plurality of duct means 25 for containing the refrigerant medium. The two sheets of metal, 22 and 23, may be welded together, or otherwise suitably secured, so that 5 the duct means 25 will be fluid tight. The duct means 25 extend vertically along the side walls 20 of the evaporator 6, from front to rear thereof, and extend from the sides partway across the top wall 18 of the evaporator toward its 10 center, and separately connect to the header 7 adjacent the bottom thereof. In this type of evaporator, the duct means also extend partway across the bottom wall 19 toward the center of the evaporator, as at 27, and terminate in 15 closed ends, and it is in these end portions that lubricant has a tendency to concentrate and prevent proper ebullition of the refrigerant medium, which condition also exists to a certain degree in other types of evaporators. The refrigerant medium, in liquid form, is contained in the ducts 25 and in the header 7, and when heat is absorbed by the refrigerant, ebullition takes place and the gaseous refrigerant collects in the upper portion of the header 7.

25 In order to provide for the proper ebullition of the refrigerant in the evaporator and to do so in an economical manner, I arrange the refrigerant supply conduit 10 with a portion 29 thereof so that the refrigerant passing therethrough is in good heat transfer relation with the refrigerant in the evaporator 6. One or more loops of the refrigerant supply conduit 10 may be arranged beneath the bottom wall 19 of the evaporator 30 and may be welded thereto, or otherwise suitably secured to the evaporator. If the evaporator is 35 of the type shown, having the duct means 25 terminating along the bottom wall of the evaporator, it is desirable that the portion 29 of the supply conduit 10 be arranged adjacent the terminal ends of the duct means, as shown in Fig. 2.

A complete operation of the refrigerating system is as follows: The compressor 1 supplies 40 liquid refrigerant through the supply conduit 10 and which refrigerant is relatively warm compared to the refrigerant in the evaporator. As a result, the relatively colder refrigerant in the evaporator absorbs some of the heat of the relatively warmer refrigerant in the supply line as it 45 passes through the portion 29 of the conduit and which induces ebullition of the refrigerant in the evaporator to occur. By this arrangement, concentrating of the lubricant in the lower regions of the duct means 25 is prevented and the lubricant is induced to vaporize and return to the compressor. After the refrigerant in the supply line 10 flows beneath the evaporator, it is delivered to the thermostatic control 50 device which controls the admission of the refrigerant to the evaporator to maintain the level of the liquid refrigerant in the evaporator at a predetermined level. Gaseous refrigerant and vaporized oil is withdrawn from the evaporator header 7 through the suction line or return conduit 11 by the compressor when the temperature of the evaporator increases above a predetermined temperature. The compressor then compresses the gaseous refrigerant and delivers 55 it to the condenser from whence it passes to the receiver 5, in its liquid form, to be again delivered to the evaporator and the cycle repeated.

An advantage of employing the relatively 70 warmer refrigerant in the supply line to agitate the relatively colder refrigerant in the evapo-

rator is that when the refrigerant is admitted to the evaporator, its temperature will be substantially the same as the temperature of the refrigerant in the evaporator with the result that there will be comparatively little gasification of 5 the refrigerant upon its entrance to the evaporator. When refrigerant is admitted to a flooded type of evaporator and the refrigerant is relatively warmer than the refrigerant in the evaporator, it gasifies immediately upon its entrance 10 into the header of the evaporator in accordance with the difference between its temperature and the temperature of the refrigerant in the evaporator. As a result, when the valve of the control device opens to admit refrigerant to a flooded 15 type of evaporator, there is usually a tendency for the level of the liquid refrigerant in the evaporator to lower because a large percentage of the compressor capacity is used in withdrawing the gasified refrigerant from the header, 20 and the lowering of the level of the refrigerant in the evaporator causes the valve to remain open longer than it would normally remain open. Then, when the valve closes, the entire capacity 25 of the compressor is transferred to the liquid refrigerant in the evaporator and causes the level thereof to rise to the point where the liquid refrigerant overflows into the suction line. By introducing the refrigerant into the evaporator at substantially the same temperature as 30 the refrigerant in the evaporator, it will be seen that the above objectionable conditions are overcome and that the system operates much more efficiently.

From the foregoing description it will now 35 be appreciated that I have provided a new and improved refrigerating system and one which is efficient in operation. By agitating the refrigerant medium in the evaporator, lubricant will be prevented from concentrating therein and 40 it will be appreciated that by using the relatively warmer refrigerant in the supply line to cause agitation of the refrigerant in the evaporator, the objectionable conditions in the system are overcome in a very inexpensive manner. In addition, the refrigerant in the supply line is introduced into the evaporator at substantially the same temperature as the refrigerant in the 45 evaporator, with the result that the system operates much more smoothly than it would if there were a relatively large temperature differential between the temperature of the refrigerant in the evaporator and the temperature of the refrigerant being admitted to the evaporator. 55

What I claim and desire to secure by Letters Patent of the United States is:

1. Refrigerating apparatus comprising a refrigerant evaporator, a refrigerant condensing element, a refrigerant supply conduit leading from said refrigerant condensing element to said refrigerant evaporator and arranged so that the relatively warmer refrigerant passing therethrough is in heat transfer relation with the relatively colder refrigerant in the evaporator so as to induce ebullition of the same, and a return conduit connecting said evaporator and said condensing element. 60

2. Refrigerating apparatus comprising a refrigerant evaporator, a refrigerant condensing element, a refrigerant supply conduit connecting said evaporator and said condensing element and having a portion thereof intermediate its ends arranged in good thermal contact with said evap- 65 70 75

5 orator whereby the relatively warmer refrigerant passing through said supply conduit induces ebullition of the relatively colder refrigerant in said evaporator, and a refrigerant return conduit connecting said evaporator and said condensing element.

3. Refrigerating apparatus comprising a refrigerant evaporator, a refrigerant condensing element, a refrigerant supply conduit connecting 10 said evaporator and said condensing element and having an intermediate portion arranged beneath said cooling element so that the relatively warmer refrigerant passing through said conduit is in heat transfer relation with the relatively colder refrigerant in the evaporator whereby to induce 15 vaporization of the refrigerant in the evaporator, and a refrigerant return conduit connecting said evaporator and said condensing element.

4. Refrigerating apparatus comprising a refrigerant evaporator, a refrigerant condensing element, a refrigerant supply conduit connecting 20 said evaporator and said condensing element and through which refrigerant at a relatively higher temperature than the temperature of the refrigerant in the evaporator is delivered by the condensing element to the evaporator, said conduit extending beneath said evaporator and in contact therewith so that the relatively warmer refrigerant passing through the conduit will heat 25 and induce ebullition of the refrigerant in the evaporator, and a return conduit connecting the 30 said evaporator and said condensing element.

5. Refrigerating apparatus comprising a refrigerant evaporator, a refrigerant condensing element, a refrigerant supply conduit connecting 35 said evaporator and said condensing element, said conduit having an intermediate portion between the condensing element and the evaporator disposed beneath the evaporator along the bottom 40 thereof and in heat transfer relation with the relatively colder refrigerant in the evaporator so that the relatively warmer refrigerant in said conduit will induce ebullition of the refrigerant in the evaporator, and a refrigerant return conduit connecting said evaporator and said condensing 45 element.

6. Refrigerating apparatus comprising a refrigerant evaporator, a refrigerant condensing element, a refrigerant supply conduit connecting 50 said evaporator and said condensing element, said supply conduit having a portion thereof extending beneath and connected to the bottom wall of said evaporator with the relatively warmer refrigerant passing through said supply conduit in heat

transfer relation with the relatively colder refrigerant in said evaporator to induce ebullition of the refrigerant in the evaporator, and a return conduit connecting said evaporator and said condensing element.

5

7. In a refrigerating system having a flooded type refrigerant evaporator, a condensing element, a return conduit connecting said evaporator and said condensing element, and a refrigerant supply conduit connecting said evaporator 10 and said condensing element and having a portion thereof in heat transfer relation with the evaporator whereby the relatively warmer refrigerant in the supply conduit heats the relatively colder refrigerant in the evaporator to aid ebullition 15 of the refrigerant in the evaporator.

8. In a refrigerating system having a flooded type refrigerant evaporator, a condensing element, a return conduit connecting said evaporator and said condensing element, and a refrigerant 20 supply conduit connecting said evaporator and said condensing element and having a portion thereof in heat transfer relation with the evaporator whereby the relatively warmer refrigerant in the supply conduit heats the relatively colder 25 refrigerant in the evaporator to aid ebullition of the refrigerant in the evaporator, and an expansion valve controlling the admittance of the refrigerant to the evaporator.

9. Refrigerating apparatus comprising a refrigerant evaporator, a refrigerant condenser, a conduit connecting said refrigerant evaporator and said refrigerant condenser for the passage of a refrigerant medium, said conduit being arranged 35 so that the relatively warm refrigerant medium passing therethrough is in heat transfer relation with the relatively cold refrigerant medium in the evaporator so as to induce ebullition of the refrigerant medium in the evaporator.

10. Refrigerating apparatus comprising a refrigerant evaporator, a refrigerant condenser, a conduit connecting said refrigerant evaporator and said refrigerant condenser for the passage of a refrigerant medium, a second conduit for the 40 passage of a refrigerant medium, said second-named conduit having a portion thereof arranged in heat conducting relation to said refrigerant evaporator so that the relatively warm refrigerant medium passing through said second-named 45 conduit is in good heat transfer relation with the relatively cold refrigerant medium in the evaporator so as to induce ebullition of the refrigerant medium in said refrigerant evaporator.

DANIEL D. WILE.
